(57) **CLAIM**

The ornamental design for an edge of a blow-molded plastic table top, as shown and described.

DESCRIPTION

FIG. 1 is a perspective view of an edge of a blow-molded plastic table top of the present invention;

FIG. 2 is an enlarged perspective view of the edge of the blow-molded plastic table top shown in FIG. 1;

FIG. 3 is a top plan view of the edge of the blow-molded plastic table top shown in FIG. 2;

FIG. 4 is a right side view of the edge of the blow-molded plastic table top shown in FIG. 2, and with the left side view being a mirror image thereof; and,

FIG. 5 is a bottom plan view of the edge of the blow-molded plastic table top shown in FIG. 2.

The broken lines are for environmental purposes only and form no part of the claimed design.
